UNITED STATES PATENT OFFICE.

ELMER BELL, OF MT. PLEASANT, PENNSYLVANIA, ASSIGNOR TO BRYCE BROTHERS COMPANY, OF MT. PLEASANT, PENNSYLVANIA, A CORPORATION OF PENNSYLVANIA.

DESIGN FOR A PITCHER.

Application filed May 3, 1922. Serial No. 2,074. Term of patent 14 years.

To all whom it may concern:

Be it known that I, ELMER BELL, a citizen of the United States, residing at Mt. Pleasant, in the county of Westmoreland and State of Pennsylvania, have invented a new, original, and ornamental Design for Pitchers, of which the following is a specification, reference being had to the accompanying drawings, forming part thereof, in which is

shown in side elevation a jug embodying my new design.

I claim:
The ornamental design for a pitcher as shown.

In testimony whereof, I have hereunto set my hand.

ELMER BELL.
